UNITED STATES PATENT OFFICE.

LOUIS E. F. WACHTER, OF NEW YORK, N. Y.

ATTACHMENT FOR WATCHES.

1,326,811.

Specification of Letters Patent. Patented Dec. 30, 1919.

Application filed January 9, 1917, Serial No. 141,369. Renewed August 5, 1919. Serial No. 315,565.

To all whom it may concern:

Be it known that I, LOUIS E. F. WACHTER, a citizen of the United States, residing in the city and county of New York, State of New York, have invented certain new and useful Improvements in Attachments for Watches, of which the following is a specification, reference being had to the accompanying drawings, illustrative of particular

10 embodiments of my invention.

My invention relates to watches in general. Among its objects is the provision of advantageous means to be secured or otherwise applied to a watch and afford means 15 to support the watch. This supporting of the watch may be by way of holding it upright or standing; and the construction provides means to protect the side of the watch where such means are secured. In particular, this invention is intended to provide a simple, effective and otherwise advantageous device of this character. It also affords 20 a means for decorations, or added decorations, by way of bejeweling, decorating, filigree or carving to transform the general appearance and otherwise, as will herein-after appear.

A specific embodiment of my invention is shown in the accompanying drawings, in 30 which,—

Figure 1 is a face view of an ornamental frame attachment.

Fig. 2 is a side view of the same showing its attachment to the watch.

In Figs. 1 and 2, R' is an ornamental attachment frame. Q is a tube which is hinged to the frame by means of hinge pins p p. F'' is a hinged clip, G'' is the engaging pin of the watch case K', and H'' is the hinge connection between clip and frame. R'' is a crystal for the frame, and coöperates with the frame to protect the watch when attached thereto. A'' is the pendant post of the watch case K', and in attaching 40 the frame to the watch case the tube Q is slipped over the post A'', thus making a very secure attachment of the frame to the watch case. When the tube Q is placed over the post A'', the crown of the watch case 45 is temporarily removed, and the crown when replaced holds the tube in position. Thus the tube Q may rotate on the post and the frame R', may, when released by the hinged plate F'', be turned half way around and 50 become a support for the watch by way of holding it upright or standing. The crystal

R'' may be omitted or replaced by any desired construction; and in this and other respects I do not wish to confine myself to the particular form shown and specifically 60 described, but refer to all devices coming within the scope of my claims, with or without various detailed modifications and ornamentalations, or additional elements set forth in this specification.

Without confining myself to the particular embodiment herein described, what I claim and desire to secure by Letters Patent is:

1. A frame for a watch having an engaging means adjacent the post thereof, comprising a collar adapted to closely fit and swivel on the post of the watch, a main frame portion, a hinged joint between said collar and main frame portion adapted to permit the latter to swing away from the 75 watch, means on the diametrically opposite side of said frame engaging means on the watch case diametrically opposite the post, to detachably hold said frame against the watch, means on the inner periphery of 80 said frame adapted to secure a disk, and a disk coöperating with said means adapted to protect the face of the watch.

2. A frame for a watch having an engaging means opposite the post thereof, comprising a tube fastened thereto by a hinged joint at one side and adapted to engage the watch post, whereby it may turn thereon, means at the diametrically opposite side of said frame coöperating with means on the 90 watch case opposite the post thereof, whereby the frame may be clipped against the side of a watch.

3. In combination with a watch case having an engaging means opposite the post 95 thereof, a post, a face-protecting and supporting member adapted for ready attachment to and detachment from said post, including a tube adapted to pass over and fit around said post, whereby the same may 100 rotate thereon, a hinged joint connecting said tube with one portion of the periphery of said face-protecting and supporting member, a crown adapted to keep the tube in position on the post, and means on the 105 face-protecting and supporting member on a peripheral portion opposite said hinged joint, adapted to coöperate with said engaging means on the watch when not in use as a support.

4. In combination with a watch case having an engaging means opposite the post

thereof, a supplementary reversible protective frame and support, a head portion therefor hinged to said frame and adapted to encircle and rotate on the post of said watch, 5 means on the inner edge of said frame to engage and secure a plate, a plate adapted to be engaged and supported thereby, and means on said frame to detachably hold the

frame in a position against the front of the watch. 10

Signed at New York, this 8th day of January 1917.

LOUIS E. F. WACHTER.
